RADIO RECEIVING SYSTEM

Winfield R. Koch, Wilkinsburg, Pa., assignor to
Westinghouse Electric & Manufacturing Company, a corporation of Pennsylvania

Application May 27, 1929, Serial No. 366,357

9 Claims. (Cl. 179—171)

My invention relates to radio systems and particularly receiving systems of the type wherein a plurality of tuning reactors are connected together for simultaneous actuation.

More especially, my invention is concerned with radio receiving systems of the type known as superheterodynes, wherein a local oscillator is employed for changing the frequency of an incoming carrier wave to either a lower or a higher frequency before amplification and demodulation.

Superheterodyne systems, as at present constructed, have many advantages over systems of the straight amplifier-detector type but trouble has heretofore been experienced in preventing them from responding to undesired frequencies which differ from the frequency of the oscillator by an amount equal to one-half of the difference in frequency between the desired frequency and the said undesired frequencies. Such undesired frequencies are known as "image" frequencies. It has also been found difficult to so arrange the various circuits that the rotors of all of the tuning condensers may always be maintained at ground potential, insofar as radio frequency is concerned.

Superheterodyne receiving systems have also, by reason of their extreme sharpness of tuning, been somewhat unsatisfactory, insofar as the quality of music reproduction is concerned.

It is, accordingly, an object of my invention to provide a radio receiving set of the superheterodyne type wherein all of the necessary tuning condensers may be maintained at ground potential, insofar as radio frequencies are concerned.

Another object of my invention is to provide a radio receiving set of the type described wherein the selectivity is improved without sacrifice of tonal quality.

Another object of my invention is to provide a radio receiving set of the type described wherein a common source of plate potential may be utilized without causing the generation of undesirable oscillations.

Another object of my invention is to provide a radio receiving system that shall be relatively insensitive to extraneous and interfering disturbances.

Another object of my invention is to provide a radio receiving system wherein the grid-biasing potentials for all of the necessary thermionic tubes may be derived from a common source of plate potential in such manner as to preclude the generation of undesired oscillations.

Another object of my invention is to provide, in a receiving system of the type described, a plurality of independent means for volume-control.

Another object of my invention is to provide a radio receiving system that shall comprise devices for simulating the action of a band-pass filter.

Another object of my invention is to provide a radio receiving system, the tuning of which is unaffected by changes in the energy-receptor or antenna to which it is connected.

A still further and more specific object of my invention is to provide a radio receiving system that shall be equally well applicable to the reception of telephone signals or continuous-wave telegraphic signals.

The novel features that I consider characteristic of my invention are set forth with particularity in the appended claims. Inasmuch as the invention itself, however, comprises numerous elements and sub-elements, all combining to permit the attainment of the aforementioned objects and other objects hereinafter referred to, it will best be understood from the following description of a specific embodiment, when read in connection with the accompanying drawings.

Fig. 1 of the drawings is a diagrammatic view of a complete radio receiving system of the superheterodyne type comprising preferred embodiments of my invention.

Fig. 2 illustrates a modification of the radio frequency portion of the circuit of Fig. 1.

A receiving system illustrated in Fig. 1 comprises a coupling tube 1, a first radio frequency amplifying tube 2, a second radio-frequency amplifying tube 3, a first detector tube 4, to which is coupled an oscillation generator 5, a first high intermediate frequency amplifier tube 6, and a second detector tube 7. A plurality of oscillation generators 8 and 10 are coupled to the second detector tube 7, for purposes which will hereinafter be referred to more in detail, and the second detector tube is followed by a second high intermediate-frequency amplifier tube 11, a third detector tube 12, a first audio-frequency amplifier tube 13, and a power audio-frequency amplifier tube 14.

Each of the tubes in the receiving system is of the equipotential-cathode type, comprising an anode 20, a control grid 21, a thermionic cathode 22, and a cathode heater 23. The choice of tubes of this particular type, in connection with the circuits later to be described, is an intentional part of my invention.

The radio receiving system is supplied with cathode-heating current, grid-biasing potentials and plate potentials from a rectifier 24 which is arranged according to the description on page 141 of the publication by Van der Bijl, "Thermionic Vacuum Tubes," and needs no specific description. The use of a plurality of equi-potential cathode tubes 25 and 26 in the rectifier, however, is a part of my inventive thought, inasmuch as it permits the energizing of all of the cathodes in the radio receiving set proper from the same source that is utilized to energize the said rectifier tubes.

The rectifier is provided with an output resistor 27 across which is developed approximately twice the potential delivered by the secondary winding 28 of the power transformer 30, in the manner explained in the aforesaid Van der Bijl publication.

20 A plurality of conductors 31, 32, 33, 34, 35 and 36 extend from points on the output resistor that are maintained at +200, +90, +45, zero, -4.5, and -9 volts, respectively. These conductors will be later referred to as "bus-wires" 25 in describing the manner in which the various grid, plate, and cathode potentials are supplied to the receiving system.

Before attempting to explain the specific manner in which the various objects of my invention 30 are attained, it is considered advisable at this point, to briefly describe the manner in which the system operates in the reception of continuous-wave signals. For purposes of explanation, it is assumed that it is desired to receive an 35 incoming signal of the continuous wave type having a carrier frequency of the order of 500 kc.

The carrier frequency, together with other incoming frequencies and disturbances, is impressed across a resistor 40, one end of which 40 is connected to the grid of the coupling tube and the other end of which is connected to the cathode of the tube through a condenser 41, an inductor 50 and a condenser 51. The purpose of the circuit 50-51 will be hereinafter described 45 in detail.

The amplified signal then traverses the first and second RF amplifying tubes 2 and 3 the input circuits of which are tuned to the frequency of the incoming signal, and is impressed upon 50 the input circuit of the first detector tube 4. The first RF oscillator 5 is so adjusted if the incoming signal is at a frequency of 500 kc., as to generate oscillations at a materially higher frequency, 1000 kc. signals being a good value to 55 choose in the specific example given. Beat-frequencies of 500 kc. and 1500 kc. will, accordingly, exist in the output circuit of the first detector tube 4, and either of these frequencies may be chosen for further amplification. In 60 order that the selectivity of the system may be improved, I find it preferable to choose the higher frequency, namely, 1500 kc. and the input circuit of the highest intermediate frequency tube 6 is accordingly tuned thereto.

65 The output of the higher intermediate frequency tube 6 is impressed on the input circuit of the second detector tube 7 wherein, by reason of the action of the second high-frequency oscillator 8, it is altered to either a higher or to a lower second intermediate frequency, and is thereafter amplified by the second intermediate-frequency amplifier tube 11.

If the incoming signal is of the continuous-wave type a beat-frequency oscillator may be

utilized to reduce the signals to an audible note for further amplification.

The second intermediate frequency is demodulated in the third detector tube 12, and the resulting audio-frequencies are next impressed upon the first audio-frequency amplifier tube 13, and, thereafter, upon the second audio-frequency or power-amplifier tube 14.

By reason of the successive heterodyning of the incoming signal by the first and second high-frequency oscillators, the desired signal may be widely separated from interfering signals before amplification in the second intermediate amplifier. This feature is of particular value, under present conditions, since signals from many stations, which would otherwise interfere, and which lie within the range of receiving sets of the usual superheterodyne type, are thus prevented from being heard.

In addition to the general arrangement of the 20 circuits thus far described, my invention further consists in the specific circuit details of the various stages, which details, in their entirety, mutually contribute toward sensitivity, selectivity and ease of operation. These details will now be 25 taken up in their proper order, and an effort will be made to point out the novel features of each.

It will be noted that an inductor 50 and a variable condenser 51 are included in the cathode circuit of the coupling tube 1, a radio-frequency choke-coil 52 being connected in shunt to the variable condenser. The inductor and the condenser constitute a tunable circuit that may be adjusted to the frequency of the desired incoming signal, to a slightly higher frequency or to a slightly lower frequency. When the circuit is adjusted to the frequency of the desired signal, the coupling tube will amplify the said signal to the exclusion of signals at adjacent frequencies, irrespective of the fact that the input circuit of the tube is aperiodic.

As shown in Fig. 2 of the drawings, one or 45 more radio-frequency amplifying stages 123 and 124 for example, may be interposed between the coupling tube 1 and the first radio-frequency tube 2, each of the stages preferably comprising 50 an equi-potential cathode tube, the cathode circuits of which may include reactors 125 and 126 similar to the reactors 50 and 51 in the cathode circuit of the coupling tube. By tuning one of the said stages to a frequency somewhat lower than the desired frequency and by tuning another of the stages to a frequency higher than the desired frequency, a band-pass filter effect 55 may be secured without resorting to expensive band-pass filters. In fact, the shape of the response curve of the receiving system may be so adjusted as to have any desired contour.

It is often desirable, in the event that the receiving system is used at a point closely adjacent to a higher-power transmitter, to interpose a wave trap in the input circuit thereof. It is much better, however, to incorporate means equivalent to a wave trap directly in the receiving system itself. For that reason, I have included a parallel resonant circuit, constituted by an inductor 60 and a tuning condenser 61, in the cathode circuit of the first radio-frequency tube 2. When this circuit is tuned to a strong interfering signal, it prevents the first radio-frequency stage from amplifying the said signal and, although the interfering signal may be impressed upon the input circuit of the said radio-frequency stage, it will not be amplified and appear in the output 75

circuit thereof. The circuit 60-61 also has the important function of reducing image-frequency response, when properly tuned.

It often happens, in the operation of sensitive 5 tuned radio-frequency amplifiers, that parasitic oscillations at ultra-high frequencies, or at high frequencies lying within the tuning range, are developed. In order that such oscillations may be minimized, I have included a variable reactor 10 62 in the cathode circuit of the second radio-frequency amplifying tube. This reactor, when properly adjusted, tends to stabilize the system and to prevent oscillations at high frequencies.

As previously pointed out, it is highly desirable 15 that the rotors of all the tuning condensers shall be maintained at ground potential, insofar as radio frequency is concerned. It is also desirable that the various oscillation generators and the amplifying tubes shall be supplied with plate potential 20 from the same source. In addition, I have established the fact that an oscillator of the so-called Hartley type is, perhaps, the best to use in a superheterodyne receiver. These desirable features cannot be satisfactorily attained if the 25 25 mionic tubes of the usual filament type are employed, since it is impossible to maintain the filaments thereof at varying potentials with respect to each other, inasmuch as they must all be supplied with power from the same source. By 30 choosing equi-potential cathode tubes, however, I am enabled to maintain any desired potential differences between the grids and cathodes thereof, between the anodes and grids thereof, between the anodes and cathodes thereof and between the 35 several cathodes.

It will be noted, from an inspection of the drawings, that a coupling coil 63, for the first oscillator 5, is serially connected between the cathode of the first detector tube 4 and the bus-wire 34, which wire is maintained at effective 40 ground potential, insofar as radio frequency is concerned, by reason of the by-pass condenser 41, connected between it and the ground. The rotor of a tuning condenser 64, comprised in the input 45 circuit of the first detector tube, and the rotor of a frequency-determining condenser 65, associated with the oscillation generator, are also connected to the conductor 34 by short leads 66 and 67 respectively, thus maintaining the rotors effectively at ground potential. It will further be noted that the oscillating potentials from the 50 oscillation generator tube 5 are applied simultaneously to the grid and the anode of the first detector tube, in phase. The oscillator is, therefore, not quite so effective as in systems of the usual type, but the slight lack of effectiveness is 55 more than compensated for by the advantages accruing from the grounding of the condenser rotors.

Inasmuch as the cathode of the oscillator tube has an inappreciable capacity to ground, no deleterious effects arise from grounding the rotor of the condenser. It should be apparent to those skilled in the art that these results cannot be obtained without complicated circuits, when using detector and oscillator tubes having filamentary cathodes supplied from the same power source.

In order that the volume of the signal output 70 from the entire system may be easily controlled, I have included a variable resistor 70 in the cathode circuit of the first high-intermediate-frequency amplifier tube 6. Since the entire plate current in the said tube must, of necessity, traverse the resistor, the potential applied to the

plate of the tube obviously is altered with changes in the magnitude of the resistor.

It will also be noted that a connection 71 extends from the midpoint of the inductor constituting the input circuit of the said tube to the bus-wire 35 which is maintained at 4½ volts and that, accordingly, any change in potential between the anode and the cathode of the tube, occasioned by a variation of the resistor 70, is accompanied by a change in the potential of the grid with respect to the said cathode. The volume-control resistor 70 therefore, serves to control the amplification in the first high-intermediate-frequency amplifier both by occasioning variations in the plate potential applied thereto and in the grid potential with respect to the cathode thereof.

The second high-frequency oscillator is coupled to the second detector through an inductor 80 that is included in the cathode circuit of the 20 said tube. The advantage of this type of coupling has been previously mentioned in connection with the first detector tube.

The beat-frequency oscillator is coupled to the second high-frequency oscillator through an inductor 81 which is included in the cathode circuit of the said second high-frequency oscillator. The oscillations generated by the said second high-frequency oscillator may, accordingly, be modulated at the frequency generated by the 30 beat-frequency oscillator.

A switch 82 is included in the plate circuit of the beat-frequency oscillator for the purpose of deenergizing it in the event that the incoming signals are not of the CW type.

It will be seen, from a close inspection of the drawing, that the circuits of the three oscillation generators 5, 8 and 10 differ in details although each of the three circuits is essentially of the Hartley type. The circuits so shown are interchangeable and are given merely to illustrate the manner in which my invention permits the grounding of the rotors of the tuning condensers associated therewith. The circuits of the first radio-frequency oscillator and the beat-frequency oscillator are perhaps the most satisfactory of the three circuits illustrated.

A volume-control network of alternative type is shown in connection with the second intermediate-frequency amplifier stage. The network 50 comprises a resistor 90 connected in shunt to the -B and +45 volt terminals of the output resistor of the power supply. A connection 91 is made between the cathode of the amplifier tube and a movable contact device 92 associated with the 55 resistor. The potential of the cathode with respect to both the anode and grid of the tube may, accordingly, be varied by moving the contact device toward either the positive or the negative end of the resistor.

The input circuit of the third detector tube 12 preferably comprises a grid leak 109 and a grid condenser 101. Plate potential for the third detector tube is supplied from the +200 volt bus-wire over a variable resistor 102.

The grid of the first audio-frequency amplifier tube 13 is directly connected to the plate of the third detector tube, and the potential of the said grid is, accordingly, determined by the IR drop along the variable resistor. A connection 70 103 extends from the cathode of the first audio-frequency amplifier tube to the +90 volt bus-wire, and plate potential for the tube is supplied from the +200 volt bus-wire. A potential difference of 110 volts, therefore, would normally 75

exist between the grid of the tube 13 and the cathode thereof but, by properly adjusting the no-signal plate current in the third detector tube 12, the potential drop along the variable resistor, 5 may be so determined that the grid of the said tube assumes a sufficiently negative potential to bias it almost to the cut-off point.

An incoming signal, however, causes a diminution in the plate current of the third detector 10 tube. The IR drop in the variable resistor is, accordingly, lessened to a value which permits the grid of the first audio-frequency tube to acquire a sufficiently less negative potential to permit satisfactory amplification of the fluctuating 15 audio-frequency potentials existing across the variable resistor by reason of the incoming signals.

An ammeter 120 is preferably included in the cathode circuit of the third detector tube 12 as 20 an aid in determining when the signal is properly "tuned in", accurate tuning being indicated by minimum current through the ammeter.

A loud speaker 121, or other signal indicator, is preferably included in the cathode circuit of 25 the second audio-frequency amplifier tube 14, and a resistor 122 is connected in series therewith.

The grid of the amplifier tube 14 is connected to the resistor 122 at that end to which the loud 30 speaker is also connected. The plate current flowing in the resistor, accordingly, determines the grid potential, and the tube is thus automatically biased to the best operating point.

From a careful consideration of the foregoing 35 description of a superheterodyne receiving system comprising my invention, it will be apparent that, by utilizing tubes of the equi-potential type, I am enabled to provide a receiving system that has many advantages, among which may be mentioned extreme selectivity, sensitivity, simplicity, 40 fidelity of reproduction and lessened danger to the operator from high potentials.

Although I have illustrated my invention as 45 particularly applicable to receiving systems of the superheterodyne type, it is equally useful in other receiving systems of the types well known to those skilled in the art. The description of certain specific circuit details in connection with particular stages of the systems is not to be construed as an admission that the said details are only useful in the said stages. For example, the tuning ammeter 120 might well be included in the cathode circuit of the first detector, or in the cathode circuit of the second detector, with 50 substantially the same results. The several oscillation generators 5, 8 and 10, might all comprise circuit-networks of the same type as the circuit network described in connection with any one of the said generators. In fact, substantially all 55 of the circuit details shown are capable of use in positions other than those specifically illustrated.

My invention, therefore, is not to be restricted except insofar as is necessitated by the prior art or by the spirit of the appended claims.

I claim as my invention:

1. In a radio receiving system, an electron discharge device having a grid and a cathode electrode, and an input circuit for said device comprising a resistor, a capacitor, and an inductor serially connected between said grid and cathode electrodes, said capacitor and inductor being series tuned to the frequency of an incoming signal.

2. In a radio receiving system, a plurality of electron discharge devices connected in cascade,

and means for obtaining the effects of a band-pass filter insofar as the amplifying characteristics of said devices are concerned, said means comprising tunable impedances in the cathode leads to certain of said devices, the impedance offered by said tunable impedances being different for any particular adjustment. 5

3. In a radio receiving system, a source of positive and negative potentials, an electron discharge device of the equipotential cathode type, connections between the anode, the cathode and the grid of said device and said source and a variable resistor included in the connection between the cathode and said source, said variable resistor serving to simultaneously vary the potential between the anode and the cathode as well as the grid and the cathode of said device for purposes of volume control. 10

4. In a radio receiving system, an electron discharge device of the equipotential-cathode type, 15 a tuned input circuit for said device connected between the grid thereof and said cathode, an output circuit including a source of potential, said output circuit being connected between the anode of said device and said cathode with the negative end of said source of potential at the cathode end of the circuit, the connection to the cathode being common to both said input and output circuit, and an inductor in said common connection for reducing the amplification of said device at high 20 frequencies. 25

5. In combination, a plurality of electron discharge devices having indirectly heated cathodes, 30 circuits including inductive couplings for coupling said discharge devices to constitute a radio system, a common source of potential for said discharge devices, manually variable condensers in said circuits for tuning said inductive couplings to desired frequencies of operation, each of said condensers having fixed and movable elements, 35 and a conductive interconnection between similar elements of said condensers. 40

6. In combination, an electric discharge device comprising an indirectly heated cathode, a control element and an anode, an input circuit for 45 said device including said control element and said cathode, an output circuit for said device including said anode and said cathode, an oscillation generator comprising an electron discharge device having an indirectly heated cathode, a control electrode and an anode, input and output circuits for said device including said discharge device electrodes, means for coupling said oscillation generator to said first electric discharge device and its circuits, tuning condensers in the 50 circuits associated with each of said discharge devices, and a connection between said condensers at effectively ground potential. 55

7. In a radio system, an electron discharge device having an independently heated source of 60 electrons, a plate circuit including a source of positive potential, a grid circuit having a portion in common with said plate circuit and means for varying said common portion to directly produce simultaneous effects in both said plate and grid 65 circuits.

8. In combination, a plurality of electron discharge devices, at least one of said devices having an indirectly heated cathode, circuits including inductive couplings for coupling said discharge devices to constitute a radio system, a common source of potential for said discharge devices, normally variable condensers in said circuits for tuning said inductive couplings to desired frequencies of operation, each of said con- 70 75

densers having fixed and movable elements, and a conductive interconnection between similar elements of said condensers.

9. In combination, an electric discharge device comprising an indirectly heated cathode, a control element and an anode, an input circuit for said device including said control element and said cathode, an output circuit for said device including said anode and said cathode, an oscillation generator comprising an electron discharge device having a cathode, a control electrode and an

anode, input and output circuits for said device including said discharge device electrodes, means for coupling said oscillation generator to said first electric discharge devices and its circuits, comprising an impedance in the cathode lead of said first device coupled to one of the circuits of said second discharge device, tuning condensers in the circuits associated with each of said discharge devices, and a connection between said condensers at effectively ground potential. 5 10
